[57] CLAIM

The ornamental design for a kitchen cutting board, substantially as shown.

DESCRIPTION

FIG. 1 is a top plan view of a kitchen cutting board showing my new design;

FIG. 2 is a right side elevational view thereof;

FIG. 3 is a left side elevational view thereof;

FIG. 4 is a rear elevational view thereof;

FIG. 5 is a front elevational view thereof; and

FIG. 6 is a bottom plan view thereof.

The kitchen cutting board of the invention, in the preferred embodiment, is fabricated as a single, unitary member of transparent or translucent acrylic resin having a low profile texture finish.
